PIVOTED SIDE JAW WRENCH HAVING ARCUATE GUIDE SLOT AND LONGITUDINALLY SLIDABLE ACTUATOR

Fred E. Bradley, Ferguson, Mo.

Application May 5, 1949, Serial No. 91,530

2 Claims. (Cl. 81—112)

1

This invention relates to new and useful improvements in wrenches, and more particularly those of the adjustable type.

Heretofore, most wrenches of the adjustable type commonly used have been tedious to operate, frequently requiring numerous operations before the correct adjustment corresponding to the nut or bolt head size can be effected. In many cases both hands of the user are required to accomplish the operation, since the wrench cannot be conveniently adjusted by the same hand in which it is held. Also, several proposed types incorporate two-piece handles, each piece movable with the jaw portions, thus creating the danger of pinching the operator's hand when using the wrench. Furthermore, these previous designs are often subject to considerable lateral distortion such being avoided only by designs which are heavy and unwieldy.

The principal object of this invention is to provide a wrench which can be adjusted easily in a single operation and requiring the use of only one hand.

Another object is to provide a wrench which is protected from lateral distortion, but yet is extremely light in weight, compact, and sturdy.

A further object is to provide a wrench whose operation is identical from each side, so that it can be operated substantially from the position in which it is first grasped in the hand of the operator, thus eliminating the needless requirement of occasionally rotating the wrench in the hand from its one side to the other.

A still further object is to provide a wrench which is composed of a minimum number of parts, and which can therefore be cheaply and easily manufactured.

Other objects will be apparent to those skilled in the art from the following detailed description of the annexed drawing which, by way of a preferred example only, illustrates one embodiment of the invention and wherein:

Fig. 1 is a plan view of the wrench looking toward one face and showing the jaws in a wide, open position.

Fig. 2 is a similar view looking toward the other face and showing the jaws in closely spaced relation.

Fig. 3 is a longitudinal sectional view taken along line 3—3 of Fig. 2.

Fig. 4 is an elevational view, on a reduced scale, of one side of the wrench and showing the position of the operator's hand when manipulating the wrench toward an open position.

Fig. 5 is a similar view, but showing the posi-

2

tion of the operator's hand when manipulating the wrench toward closed position.

In general, my adjustable wrench comprises a major body 6, having a handle portion 7, a jaw portion 8, and an elongated, relatively wide intermediate portion 9; a minor body 10 having a base portion 11 and a jaw portion 12; a pivot means 13; an adjusting means 14; and a retaining means 15.

Referring to Fig. 2, the intermediate portion 9 of the major body 6 has a relatively wide portion 16 containing a threaded aperture 17, a rearwardly tapering, and elongated portion 18 provided with a longitudinally extending slot 19 located substantially along the longitudinal axis thereof. A threaded aperture 22 is provided adjacent the juncture of said intermediate portion with the handle portion 7. The intermediate portion 9, as shown in Figs. 1 and 3, is of reduced thickness, as compared with the thickness of the handle portion 7 and the jaw portion 8, providing a recess 23 extending from the juncture of the intermediate and jaw portions to the juncture of the intermediate and handle portions.

As disclosed in Figs. 1 and 3, the base portion 11 of the minor body 10 is preferably of the same shape as the intermediate portion 9, and is located partially within the recess 23. The thickness of the base portion 11 is preferably equal to the depth of the recess, so that the exterior surface of the base portion will lie in the same plane as the exterior surfaces of the jaw and handle portions of the major body 6. Otherwise both sides of the wrench are continuous, relatively smooth surfaces, thus eliminating possibility of pinching the operator's hand when the wrench is in use.

The base portion 11, as in Fig. 1, is provided with transversely extending arcuate slot 20 at the wide end 24, adjacent the jaw portion 12, the arcuate slot having a countersink 25. This base portion is also provided with a longitudinally extending, elongated slot 21 congruous with the slot 19 in the intermediate portion 18, but disposed at a slightly angular relation thereto, when the wrench is in open position. A countersink aperture 26, as shown in Fig. 3, is provided in the base portion at its end adjacent the handle portion.

As shown in Fig. 3, pivot means 13 is preferably a machine screw 27, which is coextensive with apertures 22 and 26 in the major and minor bodies respectively, the screw being threaded into the aperture 22. Thus the minor body 10 is pivotally attached to major body 6 at a point

substantially in the middle of the wrench, remote from the handle portion, so as not to interfere with the operator's grip on the wrench.

The adjusting means 14, as clearly shown in Fig. 3, includes a stud 28, having button-head portions 29 at each end thereof. The stud diameter is such as to have a sliding fit in the slots 19 and 21, and is movable within the slots, so that its button-head portions are in slidable relation to the exterior faces of the intermediate 10 portion 9 and base portion 11.

The retaining means 15, as shown best in Figs. 1 and 3, may consist of a flat-head machine screw 30, the shank of which is threaded into the aperture 17 of the intermediate portion 9 of the major body. The screw 30 is coextensively mounted with respect to said aperture 17 and arcuate slot 20 of the base portion 11 of the minor body, so that the head of said screw lies entirely within the countersink 25 of the arcuate slot. Thus the head of screw 30 will not interfere with manipulation of the adjusting means 14.

To operate the wrench, it may be easily grasped as illustrated in Figs. 4 and 5, wherein it will be noted that the adjustment is accomplished by means of the thumb, which manipulates the adjacent button-head portion 29 of the adjusting means 14. The wrench in an open position, as in Fig. 1, is brought into embracing relation with a nut or bolt head, that is, so that the latter is between the jaw portions 8 and 12. The adjusting means 14 is then forced forwardly, as in Fig. 5, until the nut or desired object is gripped by the jaw portions 8 and 12.

The adjustment, thereby accomplished in but one operation of the adjusting means 14, will be effectively maintained while using the wrench. Any pressure, caused by turning a nut or bolt, tends to spread the jaw portions, and this pressure is transmitted to the base and intermediate portions which apply a combined shearing and compressive force on the stud 28. This force, so produced, tends to set up a frictional force between the stud and said portions, sufficient to effectively lock the wrench in its previously adjusted position.

To remove the wrench from the object so gripped, it is merely necessary to retract the adjusting means 14, as shown in Fig. 4.

It is to be noted that the wrench so described can be operated from either face, and that its operation is identical from either face. It is to be further noted that an infinite number of adjustments can be effected within the range of the wrench.

As a result of the retaining means 15, the possibility of lateral distortion, with consequent injury to the wrench, is substantially lessened. Such injury is often caused when wrenches are accidentally dropped or if subjected to extreme operating conditions, if no means is provided to guard against such injury.

I claim:

1. In an adjustable wrench, the combination of a major body comprising a handle portion, a jaw portion, and an elongated, relatively wide intermediate portion between said handle and

jaw portions, a minor body comprising a jaw portion and an elongated, relatively wide base portion juxtaposed with respect to said intermediate portion of the major body, so that the jaw portions of said bodies are in work-engaging relationship, one of said relatively wide portions being provided with a transversely extending arcuate slot struck from an axis adjacent said handle portion, means pivotally connecting said major and minor bodies together at said axis, means carried by and reciprocable longitudinally of said elongated intermediate and elongated base portions, to swing said base portion about said axis, whereby said jaw portions may be moved toward and away from each other, and means comprising a shank extending into said arcuate slot of the one relatively wide portion and rigid with the other relatively wide portion of said bodies and a head on the shank to prevent separation of said portions of the bodies in the direction of said axis.

2. In an adjustable wrench, the combination of a major body comprising a handle portion, a jaw portion, and an elongated, relatively wide intermediate portion between said handle and jaw portions, a minor body comprising a jaw portion and an elongated, relatively wide base portion juxtaposed with respect to said intermediate portion of the major body, so that the jaw portions of said bodies are in work-engaging relationship, one of said relatively wide portions being provided with a transversely extending arcuate slot struck from an axis adjacent said handle portion, and said elongated portions of said bodies each provided with a longitudinally extending slot, said last mentioned slots located with their axes in diverging relationship, means pivotally connecting said major and minor bodies together at said first mentioned axis, means comprising a shank extending into said arcuate slot of the one relatively wide portion and rigid with the other relatively wide portion of said bodies and a head on the shank to prevent lateral separation of said portions of the bodies in the direction of said first mentioned axis, and means comprising a stud extending thru said longitudinally extending slots and having a diameter substantially equal to the width thereof and a button-head portion on each end of said stud, rigid therewith and overlying the outer face of that elongated portion of the body adjacent its respective end of the stud, for swinging said base portion about said first mentioned axis, whereby said jaw portions are moved toward and away from each other upon manipulation of said last mentioned means.
